SIGNORS TO TRICO PRODUCTS CORPORATION, OF BUFFALO, NEW YORK

HORN

Application filed March 18, 1931. Serial No. 523,621.

This invention relates to a fluid pressure operated horn for giving a warning note or signal, the horn being especially adapted and designed for use on vehicles such as automo-
5 biles and boats.

The invention comprehends a device having a sound box with a fluid pressure actuated sound generating valve and an elongated trumpet passage for directing and augmenting the sound waves produced in the sound box. The valve, which is caused to oscillate toward and away from a valve seat by a difference in fluid pressure exerted against its opposite faces, is supported by resilient members arranged in a novel manner, rendering the device susceptible of economical manufacture and of ready adjustment to secure the desired sound effect. The resilient members which support the oscillator or 10 valve are disposed co-axially of its axis of oscillation, thereby permitting of comparatively free angular movement of the valve relative to the axis of oscillation to allow it to seat properly.

25 These and other objects and advantages will become apparent from the following description of a typical embodiment of the invention, reference being made to the accompanying drawings, wherein:

30 Fig. 1 is a side elevational view of the completed device.

Fig. 2 is an enlarged central longitudinal sectional view, showing the inner end of the trumpet, the sound box, and the elements 35 contained in the latter.

Fig. 3 is a transverse sectional view, taken approximately upon line 3—3 of Fig. 2.

Fig. 4 is a perspective view of the sound box rear casing section.

40 Fig. 5 is a disassembled view of the sound generating valve and the supporting means therefor, the resilient members being omitted.

As shown in Figs. 1 and 2, the device comprises an elongated tapered trumpet 10 with a bell shaped forward end 11. The inner end 12 of the trumpet may be of heavier metal and screw threaded for attachment to the forward casing section 13 of the sound box, a fluted locking nut 14 being provided to lock 45 the parts 12 and 13. The rear interior of the

casing section 13 is screw threaded to receive the rear casing section 15, shown in Fig. 4, which comprises a forward threaded plug portion 15' and a shank having a non-circular end 16. A set screw 17 may be threaded into the casing section 13 to lock the section 15 in the desired position relative to the forward section. Seated in an annular recess about the latter is a light metal cap 18 which lends a finished appearance to the device and prevents exposure of the surfaces of adjustment of the casing sections.

The interior of the casing comprises a chamber 19, communicating with a fluid exhaust tube 21 which may extend to the exhaust manifold of an internal combustion engine or other source of fluid under pressure less than that maintaining in the passage of trumpet 10, in the device illustrated. The casing defines another chamber 22, which in this embodiment is within the confines of the trumpet member, and which communicates with the trumpet passage through a reduced neck 23. A sound creating valve or oscillator 24 is disposed within the chamber 19 and is adapted to seat against the surface 25 to close communication between chamber 19 and chamber 22. The oscillator may be mounted upon a shank 26, being retained thereon by a heavy nut 27, which may also function to increase the inertia of the valve assembly and reduce its rate of oscillation.

The valve assembly is suspended by a pair of springs 28 and 29, the latter extending into a well 31 in the rear casing section and being attached to the shank 26 and a headed pin 32 which extends into the well. Spring 28 may be attached to the shank 26 and anchored to a pin 33 extending through the trumpet member, the pin being retained against displacement by the locking nut 14. Both springs may be placed under the desired tension by turning the casing section 15 outwardly. It has been found to be preferable to form the spring 28 relatively long and the spring 29 relatively stiff, although the springs may be made of the same or any other desired relative proportion.

In operation the greater fluid pressure maintaining in the chamber on the forward

side of the valve 24 will cause the valve to open, relieving the tension on the spring 29 and increasing that of the spring 28. The valve will remain open until the pressure differential between the chambers 28 and 29 is less than the urge of the springs to move the valve to seated position, the latter movement occurring when the pressures assume this relation. Fluid in the chamber 19 will then 10 exhaust through the passage 21 until the pressure differential is again sufficient to unseat the valve. The reciprocation of the valve thus effected will set the air within the sound box into sound effecting oscillation, the sound waves being amplified and directed by the trumpet passage. The rate of the oscillation of the valve and the pitch of the sound signal produced thereby will be dependent upon the weight or inertia of the valve which may be 15 varied by substituting nuts of different size for that indicated at 27, or the rate may be changed by varying the tension of the springs by rotating the rear casing section.

When the springs are of approximately the 25 relative sizes illustrated, it will be noted that the heavier spring 29 is under maximum tension when the valve is closed, the tension decreasing as the valve opens. The lighter, longer spring 28 is under minimum tension 30 when the valve is seated and under greater tension when the valve is unseated. By reason of the unequal sizes of the springs, the initial tension, or tension holding the valve to its seat and resisting initial opening movement, can be very readily regulated, since 35 substantially all of the longitudinal movement of the adjustable member will be taken up by the lighter and longer spring. Upon opening movement there will be less tendency 40 for springs, having this relationship, to permit the valve assembly to sag since the lighter and longer spring will be placed under increased tension.

By reason of the coincidence of the spring 45 axes and the axis of valve reciprocation, the need for a valve guideway is eliminated, and the valve is given relatively great freedom of motion, being permitted to move slightly to one side of its normal axis of movement or 50 to move angularly in order to assume a proper seat. The construction is simple and utilizes relatively few parts, all of which are adapted to ready manufacture, assembly and adjustment.

55 It will be understood that the specific device described is merely illustrative of the principles of the invention and that these principles may be embodied in devices having other structural relationships.

60 What is claimed is:

1. A fluid pressure operated horn comprising a chamber having an inlet port and an outlet port, a reciprocatory member normally seating to close one port and adapted to be reciprocated to produce sound pulsations

when a fluid stream is caused to move through the chamber from one to the other of said ports, and a pair of spring members disposed substantially longitudinally of the path reciprocation of said member for supporting it, said springs being disposed on opposite sides of the member. 70

2. A fluid pressure operated horn comprising a chamber having an inlet port and an outlet port, a reciprocatory member normally seating to close one port and adapted to be reciprocated away and toward said one port when a fluid stream is caused to move through the chamber from one to the other of said ports, a pair of tensioned spring members 80 disposed substantially in the line of reciprocation of the member for supporting it, and means for adjusting the tension of said spring members. 85

3. A fluid pressure operated horn comprising a chamber having an inlet and an outlet port, a reciprocatory member adapted to close one port and adapted to be reciprocated to produce sound pulsations when a fluid stream is caused to move through the chamber from one to the other of said ports, a coiled tension spring joined to each of opposite sides of said member and disposed substantially along the line of reciprocation of the member, and means for varying the tension of said springs, 95 whereby the member may be normally supported by the springs in seated position to close one port. 90

4. A horn comprising a casing having a chamber and a sound outlet port from said chamber, a sound producing member for closing said port and adapted for vibratory movements to produce sound pulsations, a pair of spring members disposed substantially in the line of vibratory movement of said 100 sound producing member and joined to opposite sides of said sound producing member for normally retaining it in a predetermined relationship to said casing, and means for effecting vibratory movements of the sound 105 producing member. 110

5. A horn comprising a casing having a chamber and a sound outlet passage in communication with the chamber, a pair of coil springs under tension disposed end on end 115 in said chamber and port and substantially perpendicular to a seat formed in the casing at the juncture of the sound outlet passage and the chamber, and a vibratory member normally disposed against said seat and joining said springs, one of said springs urging said member toward the seat and the other urging it away from the seat, the latter spring being stiffer than the other spring. 120

6. A horn comprising a casing having a chamber and a port extending from said chamber, a sound producing member for closing said port and adapted for vibratory movements to produce sound pulsations, a pair of coiled springs disposed substantially 125

in the line of vibratory movement of said member and joined to opposite sides of said member for normally retaining it in closing position, the spring on the chamber side of the member being shorter and heavier than the other spring, and means for moving the heavier spring relative to the casing to vary the tension of the springs.

5 7. A horn comprising a pair of casing sections screw threaded together and together defining a chamber, a port in one section opening into said chamber, valve means in said chamber adapted to seat over said opening and to oscillate away from and toward the opening to produce sound pulsations, spring means for supporting said valve means, said spring means comprising a pair of coiled tension springs disposed one on each side of the valve means and substantially in the line 10 of its oscillatory movement, and one of said springs being joined to each of the casing sections, whereby upon relative screw movement of the sections the tension of said springs may be varied.

25 8. A horn comprising a pair of casing sections screw threaded together and together defining a chamber, a port in one section opening into said chamber, a pair of tension springs in end to end relation and extending substantially axially of said port and across said chamber, a support extending across the port of one casing section for supporting one end of one spring and means for joining the other spring to the other casing section, and 30 sound producing means between and joining said springs, whereby upon relative screw movement of the sections the springs may be tensioned to normally support the valve means in a position closing the port from the 35 chamber.

40 9. A horn comprising a casing having a chamber and a trumpet passage defining member screw threaded into the casing, sound producing means disposed in said chamber and adapted to seat against the inner end of the member, a pin extending through the member beyond the confines of the casing, a tension spring joined to the means and the pin for urging the means 45 against the member, and a locking element screw threaded to said member for retaining said pin and for locking the member and casing together.

50 10. A horn comprising a pair of casing sections having a screw threaded connection and together defining a chamber, a sound producing member disposed in said chamber, a spring secured to each of said sections, and to said sound producing member, whereby 55 upon relative screw movement of the sections the springs may be adjusted to a desired degree of resiliency, and a cap fitted to one of said sections for enclosing the other of said sections to protect the screw threaded connection.

11. A horn comprising a casing having a chamber and a trumpet passage opening into the chamber through an annular seat, a valve coacting with the seat to interrupt fluid movement through the seat, and a resilient support 70 for the valve for urging the latter to its seat, said resilient support arranged substantially coaxial of the annular seat and constituting the sole means of support for the valve, said valve being unguided in its movement to 75 and from the seat by the casing.
